WILLIAM D. DUNN, OF ELIZABETH, AND ROBERT JEFFERY'S, OF CARTERET, NEW JERSEY; SAID DUNN ASSIGNOR TO RETTA HARRIET DUNN, OF ELIZABETH, NEW JERSEY

SAMPLE THIEF

Application filed February 5, 1929. Serial No. 337,574.

This invention relates to a novel "sample thief", i. e. a device adapted to obtain a sample of liquid from a container at any desired level.

5 55 This invention has for an object to provide a sample-thief which will overcome the defects and undesirable features of previous devices and which positively will take a true sample at any desired elevation.

10 60 Another object of this invention is to provide a device of this nature adapted to be lowered into a tank or other container by a cord, which is completely closed during its descent in the liquid, and which is adapted 65 to be opened by the same cord which supports the device.

20 70 A further object is to provide a normally closed sample-thief which may be supported and opened by a single cord and which is adapted to obtain a sample at any desired elevation in the tank or to pick up a sample from the very bottom of the tank, such for example as to indicate whether, and how much, water may be present in the bottom 75 25 of an oil tank.

Other objects and advantages will be in part indicated in the following description and in part rendered apparent therefrom in connection with the annexed drawings.

30 80 To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:—

40 85 Figure 1 is a central vertical section through the improved sample thief, showing the main valve, which controls the flow of fluid into the device and also the bottom valve in their closed positions. Fig. 2 is a similar view showing both the main valve and the bottom valve in their open positions. Fig. 3 is a section on the line 3—3 of Fig. 1.

45 90 Referring more specifically to the drawings the improved sample thief is disclosed as comprising a closed chamber provided by 95 a tubular body member 1 and upper and

lower end caps 2 and 3. The end cap 2 is formed with a central aperture or port 4 normally closed by the enlarged portion 5^a of a slide valve 5, as shown in Fig. 1. The slide valve also is formed with a reduced portion 5^b and when the valve is shifted axially to the position shown in Fig. 2 the space between the reduced portion 5^b and the walls of the port 4 afford an escape for air from within the device and an inlet for oil or other liquid into which the device has been lowered. The valve 5 is normally maintained in the position shown in Fig. 1 by means of spring elements 6 secured to the end cap 2 and engaging the conical portion 7 of the valve-stem. A single cord 8 secured to the upper end of the valve-stem serves to support the sample thief and also to open the valve at the desired depth as later will be described.

50 75 To the lower end of the valve stem there is secured a cross arm or spider 9 within which is fixed two pins 10, adapted, as shown in Fig. 2, to engage the inner wall of the cap 2 and thereby limit the axial movement of the valve. It is to be understood that the device is made of such weight and proportions that it will sink within the liquid desired to be sampled, while filled with air.

80 85 The operation of the improved sample thief when taking samples at various elevations is as follows; the device filled with air, and with the valve 5 closed, as shown in Fig. 1, is lowered into liquid held within a tank or other container. When the device has reached the elevation at which the sample is desired, as may be indicated by suitable graduations on the cord 8, the operator gives the cord a jerk. This causes the conical portion 7 of the valve-stem to spread the spring elements 6 so that the valve may be moved axially relative to the body of the device to the position shown in Fig. 2. Air within the device then escapes through the port 4 and the liquid at the elevation of the port flows into the receptacle completely filling it. The device, with its sample, is then raised by the cord 8 and a true sample at a predetermined elevation in the tank is available.

90 95 Where it is desired to take samples from 100

the bottom of a tank the device is provided at its lower end with a second valve 11. This valve comprises a casing 12 secured to the end cap 3 and affording a seat for a spring-pressed plunger 13 having its end 13^a projecting through the end cap and adapted to engage the bottom of the tank. As shown in Fig. 2, contact of the end 13^a with the bottom of the tank causes the plunger to be forced upwardly against the action of the spring 14 and liquid from the bottom of the tank flows upwardly about the reduced end 13^a and through holes 15 in the casing 12 into the body member. A cap 16 may be threaded upon the member 12 to afford an abutment for the spring 14 and to guide the plunger 13.

When taking a sample from the bottom of a tank the operator lowers the device until he feels it rest upon the bottom of the tank. This of course opens the valve 11 but liquid may not flow into the device because it is then filled with air. The operator then raises the device slightly from the bottom of the tank and jerks the cord 8 thereby opening the port 4 as previously described. He immediately lowers the cord 8 until the device again rests on the bottom of the tank. As the air escapes through the port 4 liquid enters through the then open valve 11. Should any liquid enter the device through the port 4 no difficulty arises as the liquid entering through the bottom valve is necessarily heavier than that which will enter through the port 4 and therefore the liquid entering at the bottom will force out the lighter liquid and a true sample from the bottom is obtained.

One of the principal purposes of taking a bottom sample is to ascertain whether any water exists in an oil tank and if so the amount of water therein. The present device performs this task admirably well as it takes the sample directly from the bottom of the tank and will indicate the presence of as little as $\frac{1}{4}$ inch of water. Obviously when the valves are open the water in the tank will seek its level within the device and therefore a sample taken from the bottom will indicate whether, and to what depth, water is present in the tank. A glass window 17 is preferably provided in one side of the body member 1 through which the elevation of the water therein may be observed.

Throughout the specification the term "cord" has been used to define the supporting means for the casing. It is to be understood that this term is intended to cover all forms of flexible or semi-flexible elements such for example as cables, wires, chains, etc., as distinguished from a pole, rod or other rigid element.

Having thus described our invention what we claim and desire to secure by Letters Patent of the United States is:

65 1. A sample thief comprising a normally

closed casing adapted to be lowered into liquid; a cord supporting said casing; and means actuated by said cord to open said casing at any desired elevation.

2. A sample thief comprising a casing 70 adapted to be lowered into liquid; a port in said casing; a valve normally closing said port; yielding means maintaining said valve in port-closing position; and a single cord attached to said valve and serving both to support said casing and to actuate said valve to open said port at any desired elevation in said liquid.

3. A sample thief combining a normally closed casing adapted to be lowered into liquid; an intake port in said casing; a valve normally closing said port, said valve comprising a member shiftable axially relative to said casing and affording a portion of a size and shape to close said port; yielding detent means acting upon said valve to maintain said portion in port-closing position; a single cord connected with said valve and serving through said detent means to support said casing and to shift said valve axially relative to said casing thereby to move said portion away from said port to afford ingress for liquid; and means to support said casing on said valve member in its shifted position.

4. A sample thief combining a liquid tight casing adapted to be lowered into liquid; an intake port in said casing; a valve normally closing said port, said valve comprising a member shiftable axially of said casing and affording one portion of a shape and size adapted to close said port and another portion of reduced size; friction means acting upon said valve to maintain the first named portion in port-closing position and the reduced portion within said casing; a single cord connected with said valve and adapted to support said casing and by means of a jerk to overcome said friction means and shift said valve axially thereby to put the reduced portion thereof in said port to afford ingress for liquid; and means to limit the relative axial movement between the casing and valve member.

5. A sample thief as set forth in claim 3 in which the shiftable valve member is formed with a conical portion and spring elements carried by the casing frictionally engage the conical portion to support the weight of the casing on said valve member, and in which said frictional engagement is adapted to be overcome by a jerk on the supporting cord.

6. A sample thief as set forth in claim 4 in which the reduced inner end of the valve member carries a member to which are secured elements adapted to engage an inner wall of the closed casing to limit the relative axial movement between the casing and the valve member, thereby to position the reduced portion of the valve in the intake port to afford an ingress for liquid.

7. A sample thief combining a normally closed casing; a port in the upper end thereof; a valve normally closing said port; a single cord connected with said valve and adapted to perform the dual function of supporting said casing and actuating said valve; a port in the lower end of said casing; and a valve normally closing the last named port, the last named valve comprising a spring resisted member projecting from said casing and adapted to be shifted to port-opening position by contact with the bottom of a container.
8. A sample thief adapted to take a sample from the bottom of a container comprising a liquid tight casing adapted to be lowered into liquid while filled with air; an intake port in the bottom of said casing; a valve normally closing said port, said valve having a portion adapted by contact with the bottom of a container to open said port; an air exhaust port in the upper end of said casing; a slide valve normally closing the last named port; detent means normally acting to maintain said slide valve in port-closing position; a cord connected with said slide valve and adapted by a jerk to overcome said detent means thereby to open said upper port; and means positively to support said casing on said slide valve.

In witness whereof, we have hereunto subscribed our names.

WILLIAM D. DUNN.
ROBERT JEFFERYS.
